UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

MEANS FOR OPERATING DOORS.

1,185,512.

Specification of Letters Patent.

Patented May 30, 1916.

Application filed October 26, 1914. Serial No. 868,766.

To all whom it may concern:

Be it known that I, GEORGE B. KOHLER, a citizen of the United States, residing at Philadelphia, Pennsylvania, have invented 5 certain Improvements in Means for Operating Doors, of which the following is a specification.

One object of my invention is to provide a simple and effective means for opening 10 and closing doors, particularly those of passenger cars, which are usually located at the side of the car at either end, or at the middle, and which are generally arranged in pairs.

15 Another object of the invention is to so construct and arrange the mechanism that either one of the doors can be opened or closed independently of the other, or both doors can be opened in unison.

20 A further object of the invention is to construct the mechanism so that it can be located at one side of the platform, the operating elements being arranged on a horizontal pivot.

25 In the accompanying drawings: Figure 1 is a sectional plan view illustrating one end of a passenger car and platform with the two sets of doors in the closed position and the steps raised; Fig. 2 is a sectional elevation looking from the interior of the platform toward the doors and showing the doors and steps in the same position as illustrated in Fig. 1; Fig. 3 is a vertical sectional view on the line *a—a*, Fig. 1; Fig. 30

35 4 is an enlarged view of a part of the mechanism similar to that illustrated in Fig. 3; Fig. 5 is a sectional view on the line *b—b*, Fig. 4; Fig. 6 is a detached perspective view, showing the elements for connecting the 40 operating means for one set of doors and step; Fig. 7 is a perspective view showing the element connecting the other operating means to the other set of doors and step; Fig. 8 is a perspective view of the counter- 45 balance for the step, showing the step in dotted lines and in the lowered position; and Fig. 9 is a perspective view, showing the elements of the compensating means detached.

50 Referring to the drawings, 1 is the frame of the car.

2 is the platform.

3 is the outer bulkhead of a platform of the ordinary construction.

55 The doorway at one side is divided by a

post 4 and the doors 5 and 6 are made in two sections pivotally connected and the inner section of each door is pivotally mounted on the frame so as to swing to the open or the closed position. Mounted on the 60 end structure of the car body within the platform limit is a plate 7 having a bracket 8. Carried by this plate is a spindle 9 having at its upper end a handled operating lever 10. The spindle has an enlarged end 65 9^a which is provided with a pin 9^b, which enters a slot in the handle 10 so that the spindle will turn with the handle. Located between the bracket 8 and the plate 7 and secured to the spindle 9 is an arm 11, which 70 is connected by a rod 12 to an arm 13 of a three-armed lever 14 mounted on a stud projecting from a bracket 15 secured to the car frame structure under the platform. The arm 16 of the lever 14 is connected by 75 a rod 17 to an arm 18 on the lower pivot 19, which is firmly attached to a bracket 20 secured to the inner section of the door 5 so that, when the operating lever is turned, the door will be opened and closed. The 80 arm 21 of the lever 14 is connected by a rod 22 to a bracket 23 on the step 24, which is pivoted at 25 to a bearing plate 26 which is, in turn, secured to the framework of the car so that when the doors are opened the 85 step is lowered and when the doors are closed the step is raised.

The bracket 8, as illustrated in Fig. 5, has an extending hub 27 in which the shaft 9 is mounted and this hub also forms the bearing for a sleeve 28 on one end of which is the handled operating lever 29 and which has a slot to receive the pin 28^a on the said sleeve. On the other end of the sleeve is an arm 30 connected by a rod 31 to an arm 32 on a shaft 33 extending longitudinally of the car under the platform and back of the steps and this shaft is adapted to bearings 15^b, as shown in Fig. 2. On the end of the shaft is a lever 34, which is connected by a rod 35 to an arm 36 on a pivot 37 of the door 6. On the shaft 33 is an arm 38 connected by a rod 39 to the step 24^a, which is below the door 6, so that on turning the operating lever 29 the door 6, 100 and its step, can be opened or closed.

It will be noticed that the pivot 19 of the door 5 is located some distance from the end of the door and also some distance from the platform so as to allow the inner portion of 110

the door, when it swings, to extend over the platform, while the pivot 37 of the door 6 is in line with the door and when the door is in the full open position it projects entirely beyond the platform. This particular construction may be modified without departing from the essential features of the invention.

In order to lock the two levers 10 and 29 together, when it is desired to open the doors 5 and 6 simultaneously, pivot a locking lever 40 at 41 on the operating lever 29 and one arm of this locking lever is in the path of a spring push pin 42 in the handle of the lever 29 and the other arm of the lever 40 is in the form of a bolt 43, which enters a recess 44 in the operating lever so that when both doors are to be opened simultaneously, the operator grasps the handle of the lever 29 and pushes the pin 42 in with his thumb, locking the two levers together and then by turning the lever 29 both levers will turn and the mechanisms connected therewith will be operated in unison.

While I prefer to locate the operating levers at the side of the platform, as indicated, so as to be within easy reach of the conductor, whose station is at the platform, these levers may be located at any predetermined point, according to the station of the conductor, or it can be located so that the motorman can operate the doors, as in some types of cars this duty is performed by the conductor and in other type it is performed by the motorman.

In order to counterbalance the steps 24, I preferably mount a spring 45 on a rod 46, which is pivoted at 47 to a bracket 48 which carries the step pivot pin 25. This pin passes through an opening in the bracket 48 and through openings in the casing 50, which is secured to the step and is made as illustrated in Figs. 8 and 9. The casing forms a slot for the block 51, in which the end of the rod 46 is mounted. A set screw 52 extends through a threaded opening in the casing and bears against the block so as to regulate the tension of the spring 45. Thus, when the step 24 is lowered, the spring is compressed, according to the

amount of space between the pivots 25 and 47 and the spring being under compression, when the step is lowered, aids in elevating the step when it is raised.

55

I claim:

1. The combination of a platform; two doors at one side of the platform; bearings under the platform; a longitudinal shaft mounted in the bearings extending back of both doors, one of the bearings having a hub; two actuating mechanisms mounted above the platform; a lever mounted on the hub of the bearing under the platform, one arm of said lever being connected to one of the actuating mechanisms; a pivot for one of the doors to which the other arm of the lever is connected; an arm on each end of the shaft; a door pivot to which one of said arms is connected and the other arm being connected to the other operating mechanism.

2. The combination in means for operating doors, of a plate having a bearing thereon, said bearing having a tubular extension; a spindle mounted in the tubular bearing; an arm secured to the spindle at one end; an operating lever secured to the spindle at the other end; a sleeve loosely mounted on the tubular extension and having an arm at one end; and an operating lever at the other end.

3. The combination in means for operating doors, of a plate having a bearing thereon; said bearing having a tubular extension; a spindle mounted in the tubular bearing; an arm secured to the spindle at one end; an operating lever secured to the spindle at the other end; a sleeve loosely mounted on the tubular extension and having an arm at one end; an operating lever at the other end; and a latch on the last mentioned operating lever arranged to engage the other operating lever when it is desired to turn the shaft and the sleeve in unison.

In testimony whereof, I have signed my name to this specification in the presence of two subscribing witnesses.

GEORGE B. KOHLER.
